UNITED STATES PATENT OFFICE

163,756

COMBINATION SOAP DISPENSER AND MASSAGE DEVICEAbraham J. Jacobson, Chicago, Ill., assignor of one-half to Harold Jacobson, Chicago, Ill.

Application September 7, 1948, Serial No. 148,499

Term of patent 14 years

(Cl. D4—3)

To all whom it may concern:

Be it known that I, Abraham J. Jacobson, a citizen of the United States, residing at Chicago, in the county of Cook and State of Illinois, have invented a new, original, and ornamental Design for a Combination Soap Dispenser and Massage Device, of which the following is a specification, reference being had to the accompanying drawing, forming part thereof.

In the drawing:

Fig. 1 is a top plan view of a combination soap dispenser and massage device showing my new design;

Fig. 2 is a side elevational view thereof; and

Fig. 3 is an end elevational view.

I claim:

The ornamental design for a combination soap dispenser and massage device, as shown.

ABRAHAM J. JACOBSON.
